MOBILE HOT FOOD SERVER

Roy Emanuele, Massapequa, N.Y., assignor to Institutional Maintenance Corp., Brooklyn, N.Y.

Filed Jan. 7, 1972, Ser. No. 216,327

Term of patent 14 years

Int. Cl. D12—02

U.S. Cl. D55—1 E

FIG.1

FIG.2

FIG.3.

FIG.4.

FIG.5.

FIG. 1 is a perspective view of a mobile hot food server showing my new design;

FIG. 2 is a front elevational view thereof;

FIG. 3 is a rear elevational view thereof;

FIG. 4 is a top plan view thereof; and

FIG. 5 is a left side elevational view thereof.

The side opposite that shown is substantially the same as the side that is shown.

I claim:

The ornamental design for a mobile hot food server, substantially as shown and described.
